FUSE PLUG

Frank Lepore, Cicero, Ill.

Application February 8, 1946, Serial No. 646,323

1 Claim. (CL 200—113)

1

This invention relates to protective devices for electrical circuits of the type which include a current carrying conductor adapted to be ruptured when heated by the overloading of the circuit.

One object of the invention is to provide a new and improved fuse plug in which a slender filament of mercury is employed as one of the conductors, said mercury being overheated and expelled from its current conducting position by an overload in the circuit but being retained within the plug so that it is adapted to be replaced in conducting position without unsealing the plug or otherwise altering its structure.

Another object of the invention is to provide a fuse plug in which a quantity of mercury is employed as the current conductor sensitive to over-load and in which the displacement of said conductor from its normal position serves to close an alarm circuit for indicating the condition of the principal circuit in which the plug is contained.

It is also an object of the invention to provide a new and improved fuse plug of the type employing a liquid current carrying medium which is displaced from its normal current carrying position by an overload in the circuit, said plug comprising a substantially transparent body through which the displaced liquid is readily visible.

A further object of the invention is to provide equipment for protecting a plurality of circuits including a new and improved fuse plug of the type employing a liquid current carrying medium which is displaced from its normal current carrying position by an overload in the circuit, said plug including a contact element positioned in the body of the plug to contact the displaced liquid medium and to be connected therethrough with one side of a feed circuit, said element extending outside the body of the plug so that by means of a signal device and test wire connected to the other side of the circuit any such plug may be tested without removal from its mounting for determining the circuit in which the overload occurred.

Other objects and advantages of the invention will appear from the following description taken in connection with the drawings, in which:

Fig. 1 is an axial sectional view showing a fuse plug embodying this invention, with a wiring diagram therefor.

Fig. 2 is a face view of a panel board having installed thereon a plurality of fuse plugs similar to that shown in Fig. 1, with an indicator lamp for each plug;

Fig. 3 is an elevation partly in section showing

2

a modified form of the invention, with its wiring diagram.

Fig. 4 is a face view of a panel board provided with a plurality of fuse plugs like that shown in Fig. 3 and with a single indicator lamp and means for connecting it alternatively to any of the fuse plugs;

Fig. 5 is an axial sectional view of a fuse plug embodying this invention with an individual indicator lamp mounted directly on the plug, and a wiring diagram.

Fig. 6 is a transverse section taken as indicated at line 6—6 on Fig. 5.

In the form shown in Fig. 1, the fuse plug embodying this invention is provided with a body 10 which is preferably of transparent material, such as glass or synthetic plastic, and which is formed with an axially disposed chamber 12 communicating with an axial bore 14 which is slightly larger than the chamber and in which there is inserted a bushing 16 of conducting material such as brass or copper. The bushing has a slender axial channel 18 which connects with a similar channel 20 in a plug 22 of insulating material, said plug being fitted into a recess in the lower end of the conducting bushing 16 and extending through a plate or washer 24 of conducting material. Said plate 24 contacts the threaded metallic shell 26 of the plug and said shell 26 is anchored to the body 10 in any convenient manner.

The plate or washer 24 is retained in position by means of an insulating cap 28 which is held in place by the overlapping flange 30 of the shell 26 and which carries the center contact element 32 disposed axially in the cap 28 and engaged with the end of the insulating plug 22. The conducting plate 24 engages the lower end portion of the conducting bushing 16 which encircles the insulating plug 22. A small quantity of liquid current conducting material 34, preferably mercury, normally occupies the axial channel 20 in the insulating plug 22 and extends into the axial channel 18 of the conductor 16. Thus when the fuse plug is screwed into a socket connected in the circuit to be protected, the center contact 32 of the plug engages the center contact of the socket, and the shell 26 engages the threaded shell of the socket. The circuit is completed by the column or filament of mercury 34 which engages the center contact 32 and connects it with the conductor bushing 16, while the latter is connected by the plate 24 with the shell 26.

The upper or outer end of the conducting bushing 16 is formed with an inverted conical recess 36 communicating with the bore or channel 18.

Fig. 3 is an elevation partly in section showing

In the event of a short circuit or overload, the momentary overheating of the mercury 34 causes a portion of it to vaporize and expand rapidly, forcing the entire column into the chamber 12 of the body 10. This breaks the circuit and the mercury instantly cools and falls back into the recess or cup 36 into the position indicated in dotted lines at 38; but the restricted character of the channel 18 prevents the mercury from flowing by gravity into said channel and re-establishing the circuit. If the fuse plug be removed from the socket and shaken sharply, the mercury is readily forced back into the restricted channels 18 and 20, thus renewing the plug for further service, and such renewal can be repeated 15 indefinitely.

By reason of the fact that the body 10 is made of transparent material, an installation of fuse plugs of this type can be easily and readily inspected without removal from their supporting sockets, and if any of the plugs has "blown" as a result of a short circuit or overload, this fact will be readily apparent because the globule of mercury resting in the chamber 12 if the plug is in horizontal position, or in the cup 36 at 38 if the plug is installed vertically, can be seen through the transparent body 10.

The present invention provides additional means for readily and definitely identifying the plug which has been "blown" by a short circuit, and this means may be embodied in the fuse plug whether it be made of transparent or of opaque material, such as porcelain. Said means includes a conductor 40 which is permanently embedded in the body 10 so as to extend into the chamber 12 and toward the recess 36, as shown in Fig. 1. In the event of an overload or short circuit, the mercury globule formed at 38 will extend into contact with the conductor 40. Outside the body 10 the conductor is threaded so as to serve as a binding post and is provided with a knurled nut 42 for clamping one end of conductor wire 44. This wire is connected to one terminal of a signal lamp 50, while the other terminal of the lamp extends to the line wire or feed wire L¹, as diagrammatically shown in Fig. 1. The lamp or other appliance in the circuit protected by the fuse is shown at A, connected between line wires L¹ and L² with the fuse in series with the element A. When the fuse is "blown," a new circuit is established from L¹ through lamp 50, conductor 44, conductor 40, mercury 38, bushing 16, plate 24, and shell 26 which is already connected to line wire L². The lighting of the lamp 50 thus indicates that the fuse has functioned.

As shown in Fig. 2, each section of the panel board 66 includes a fuse plug body 10 and a corresponding indicator lamp 50 to which a wire 44 extends. Thus, whenever a short circuit causes the mercury 34 in a fuse plug to be expelled from its normal position in the channels 18 and 20 to its position at 38 in the recess 36, it will complete the circuit of the corresponding lamp 50 which will glow as a signal to identify the fuse plug requiring attention for renewal.

Fig. 3 illustrates a slight modification of the fuse plug structure and Fig. 4 shows a modified arrangement of the panel board. In Fig. 3 the functioning portions of the fuse device as such may be understood as similar to those of Fig. 1 already described, but instead of the conductor 40 with its binding post 42 the body portion 10a of the plug shown in Fig. 3 carries a conductor 60 having merely a smoothly rounded head 62 exposed outside the body 10a. The panel board

66 carries a single indicator lamp 70 and a single, preferably flexible, conductor 64 hangs from its connection to the socket of the lamp 70 in a position in which its contact terminal 68 is normally clear of all the fuse plug bodies 10a on the board. In the event of an overload or short circuit causing one of the plugs to "blow," the defective circuit can be promptly identified by swinging the conductor 64 so as to bring its terminal 68 selectively into contact with the exposed contact heads 62 of the several fuse plugs until such engagement causes lighting of the signal lamp 70. As a matter of convenience, the fuse plugs are shown arranged on the panel board 66 in an arc concentric with the axis of the lamp 70.

Figures 5 and 6 illustrate a further modification of the fuse plug in which it is arranged to carry its own signal lamp. The body 10b may be of transparent or opaque insulating material, and the internal portions of the fuse device itself are similar to those shown in Fig. 1 and are identified by corresponding numerals. The outer end of the plug body 10b is shown surmounted by a washer 72 which may be of fibre or like material, and serves to seat the in-turned base flange of a metallic socket 74, the base portion of the socket being bent over and enclosing an insulating disc 76 through which a bolt 78 extends into the body 10b of the fuse plug. The threaded end of the bolt extends into the chamber 12 in the plug body and is secured therein by a nut 80 which thus clamps the socket 74 in position on the outer end of the body 10b. The head of the bolt 78 serves as a center contact for the small indicator lamp 82 which is supported in the socket 74. The socket itself is provided with a lug 83, and a conductor 84 extends therefrom to the line wire L¹.

With this arrangement, it will be evident that as long as the filament or column of mercury 34 functions to complete the circuit for the lamp or other device at A through the contact element 32 and the conducting bushing 16, the lamp 82 will not be energized, but that in the event of a short circuit which causes the mercury to leave the bores 18 and 20 and to settle in the cup or recess 36, the globule of mercury thus formed at 38 will provide a connection between the line wire L², shell 26, plate 24, bushing 16 and the bolt 78 which is in contact with the center of the base of the indicator lamp 82. The other side of the circuit for the lamp 82 is already completed through the socket 74, lug 83, and conductor 84, leading to line wire L¹. Thus in any panel board containing a considerable number of fuse plugs of this type, the failure of any circuit will be indicated immediately by the glowing of the indicator lamp 82 on the plug which has been affected. The plug then may be removed and shaken down to restore the mercury to the channels 18 and 20 and thus renew the plug for further service. If the defective circuit is known to be again in safe condition, the plug will be replaced at once in its socket to resume service.

While I have shown and described herein certain structure embodying my invention and illustrative thereof, it is to be understood that the invention is not limited thereto or thereby but embraces all changes and modifications in its various features which may come within the scope of the appended claim.

I claim:

A fuse including an insulating, centrally apertured body, a conducting bushing seated therein,

closing the outer portion of the aperture and at its outer end flush with the end of the body, an insulating plug socketed in the conducting bushing and extending beyond the end of the body, a conducting washer encircling the plug, engaging the end of the body and the end of the conducting bushing, an insulating cap socketed to contain the outer end of the insulating bushing and to engage the outer face of the conducting washer, a threaded conducting shell encircling the fuse body, engaging the washer throughout substantially its entire periphery and flanged to overlie the insulating cap and hold it firmly against the washer, a conducting pin extending axially through the insulating cap, the insulating plug and conducting bushing being each centrally apertured to define an aligned capillary tube extending from the conducting pin to the inner end of the conducting bushing, the capillary tube being adapted to contain a liquid con-

5 ductor to close a circuit between the conducting pin and the conducting bushing.
